[57] CLAIM

The ornamental design for a shoe upper, as shown and described.

DESCRIPTION

FIG. 1 is a left side elevational view of a shoe upper showing our new design;

FIG. 2 is a right side elevational view thereof;

FIG. 3 is a top plan view thereof;

FIG. 4 is a front elevational view thereof; and

FIG. 5 is a rear elevational view thereof.

FIG. 6 is a left side elevational view of a shoe upper showing an alternate embodiment of our new design;

FIG. 7 is a right side elevational view thereof;

FIG. 8 is a top plan view thereof;

FIG. 9 is a front elevational view thereof; and

FIG. 10 is a rear elevational view thereof.

The broken line showing a shoe sole in FIGS. 1-10 and the area within are environmental only and form no part of the claimed design.

*FIG. 1**FIG. 2**FIG. 3*

*FIG. 4**FIG. 5**FIG. 6*

FIG. 7

FIG. 8

FIG. 9

FIG. 10

UNITED STATES PATENT AND TRADEMARK OFFICE
CERTIFICATE OF CORRECTION

PATENT NO. : Des. 305,379

DATED : January 9, 1990

INVENTOR(S) : Paul D. Brown and James A. Smith

It is certified that error appears in the above-identified patent and that said Letters Patent is hereby corrected as shown below:

Title page

On the face of the Patent, following the section marked "[75] Inventors," after "Hingham;" please delete "Judith Ringel, Milton; David E. Miller, Carver, all" and substitute therefor --James A. Smith, Boston, both--.

Signed and Sealed this

Twenty-ninth Day of December, 1992

Attest:

DOUGLAS B. COMER

Attesting Officer

Acting Commissioner of Patents and Trademarks
